[57] CLAIM

The ornamental design for a contour grading rake, substantially as shown and described.

DESCRIPTION

FIG. 1 is a top plan view of a contoured grading rake showing my new design;

FIG. 2 is a bottom plan view of FIG. 1;

FIG. 3 is an end view of the rake, the opposite end being a mirror image thereof;

FIG. 4 is a section 4—4 of FIG. 2; and

FIG. 5 is a front perspective view of the contoured grading rake.
